Inventor:
George W. Bowen,
By *George W. Bowen*

UNITED STATES PATENT OFFICE.

GEORGE W. BOWEN, OF ELGIN, ILLINOIS, ASSIGNOR TO ILLINOIS WATCH CASE COMPANY, OF ELGIN, ILLINOIS, A CORPORATION OF ILLINOIS.

METHOD OF MAKING WATCHCASES.

Application filed August 25, 1927. Serial No. 215,358.

This invention relates to a method of producing watch cases of the bracelet or wrist type in which are provided opposite pairs of lugs for holding strap bars in place.

5 It is an object of this invention to utilize in the manufacture of such cases a method or process which will be inexpensive and assure a uniform product; and to produce by the method herein described a watch case in which the lugs remain integral with the material forming the case and inseparably connected thereto.

10 The construction of the present case and the steps attending the process employed in its formation may be understood by reference to the accompanying drawing wherein—

15 Figure 1 is a perspective view of the case which is made according to the present process;

20 Fig. 2 is a plan view of the work after the first operation of blanking and drawing;

Fig. 3 is an enlarged transverse section therethrough taken on line 3—3 of Fig. 2;

25 Fig. 4 is a detail in section taken on line 4—4 of Fig. 3;

Fig. 5 which is a view similar to Fig. 3 shows the work after a second operation;

30 Fig. 6 is an enlarged transverse section therethrough taken on line 6—6 of Fig. 5;

Fig. 7 is a detail in section taken on line 7—7 of Fig. 6;

35 Fig. 8 which is a view similar to Figs. 2 and 5 shows the work after a third operation;

Fig. 9 is an enlarged transverse section therethrough taken on line 9—9 of Fig. 8;

Fig. 10 is a detail in section taken on line 10—10 of Fig. 9;

40 Fig. 11 which is a view similar to Figs. 2, 5, and 8 shows the work after a fourth operation;

Fig. 12 is an enlarged transverse section therethrough taken on line 12—12 of Fig.

45 11; and

Fig. 13 is a detail in section taken on line 13—13 of Fig. 12.

In the manufacture of a watch case, according to the present invention, I may use, in the first operation, a double acting die for blanking and forming from sheet metal a case such as Fig. 1 shows in final or finished form. When blanked and formed as shown in Fig. 2 the work comprises a plate 15 having an upstanding marginal flange 16 which

at four points is folded upon itself to provide oppositely extending lugs arranged in pairs. The lugs so provided comprise inner and outer walls 17 and 18, respectively, the latter upstanding for the greater distance (see Fig. 4), and being, in effect, continuations of higher portions of the flange 16. It will be understood that the material from which the watch case is made may be of any usual kind such, for example, as nickel having applied thereto a rolled plate of precious metal.

Having progressed to this point, the work may be annealed, should this be necessary, and then subjected to the action of a pressing die which forms it to the shape which is shown in Figs. 5, 6, and 7. In this second operation the flanges 16 are bent inwardly to a slight extent. The plate 15 may also be dished in this operation, and the higher lug wall 18 is folded over upon the other wall 17, as shown in Fig. 7.

Having progressed to this point, a further annealing of the work may be resorted to, if necessary, to keep the material in a soft or pliable condition following which a further pressing operation is performed. This results in the work taking the shape which is indicated in Figs. 8, 9, and 10, wherein it will be noted that the flanges 16 are bent inwardly to a greater extent, and the outer wall 18 of the lug is crushed down still further upon the other lug wall, as shown in Fig. 10.

The annealing operation may again be resorted to, if this be found necessary, following which the work is subjected once more to the action of a pressing die which reduces it to the shape shown in Figs. 11, 12 and 13. In this last operation the plate 15 may, if desired, be blanked out to form a case center. Should it be desired to have the lugs carried by the case back, this central portion of the plate will be left intact. In this final operation, the flanges 16 are brought to approximately the final position desired, and the two walls forming the lugs are pressed tightly one upon the other to produce a cross section which may be rectangular or substantially so, as suggested in Fig. 3.

The work which is treated to these successive operations may be subjected finally to a burnishing operation by which to smooth off and finish its interior and exterior surfaces. When this is done all

traces of the foldings in the lugs are obliterated so that the resulting product is free from any operation marks. The various steps herein described are such as to transform metal to the final product by easy stages without injury to the metal or the rolled plate which is applied thereto. It is possible to speed the progress by eliminating one or more of the pressing operations, but in order to safeguard the product, I prefer that the operations should be carried out substantially as described.

I claim:

1. The method of producing a watch case which consists in blanking a piece of sheet metal and bending the edges to form a flange and lugs the latter consisting of two adjacent walls one upstanding above the other, in pressing down the flanges and higher walls of the lugs to bend the same inwardly and fold one lug wall over upon the other, and finally in burnishing the work to smooth off the pressed surfaces, substantially as described.
2. The method of producing a watch case which consists in blanking a piece of sheet metal, in bending the edges thereof to form an upstanding flange having return bends at four points to provide lugs, and in pressing down and inwardly upon the flange to bend the same and fold one wall of each lug

over upon the other, substantially as described.

3. The method of producing a watch case which consists in forming from a metal blank a piece having a marginal flange which is bent upon itself at four places to provide adjacent walls, one higher than the other, to define lugs, and in pressing down upon the edges of the flange and higher lug walls to bend the flanges inwardly and fold over the higher lug walls upon the other lug walls, substantially as described.

4. The method of producing a watch case which consists in bending the edges of a blank to provide an upstanding flange having oppositely disposed lugs formed by return bends in the flange, one wall of each lug upstanding above the other, in annealing the case to preserve the pliability of the metal under treatment, in subjecting the case to the action of a pressing die which bends the flange inwardly and folds over the higher lug wall upon the other, in again subjecting the case to an annealing operation, and in subjecting the case again to the action of a pressing die which bends the flanges to a further degree and also folds down the higher lug wall upon the other to produce lugs having a substantially rectangular cross section, substantially as described.

GEO. W. BOWEN.
